US00D580069S

(12) **United States Design Patent**
Lee

(10) **Patent No.:** US D580,069 S
(45) **Date of Patent:** ** Nov. 4, 2008

(54) **TISSUE MICRO ARRAYER**

(75) Inventor: **Young Do Lee**, 501, 34-27,
Samjeon-dong, Songpa-gu, Seoul (KR)
138-838

(73) Assignees: **Unitma Co., Ltd.**, Seoul (KR); **Young
Do Lee**, Seoul (KR)

(**) Term: **14 Years**

(21) Appl. No.: **29/275,525**

(22) Filed: **Dec. 28, 2006**

(51) **LOC (8) Cl.** **24-02**

(52) **U.S. Cl.** **D24/216**; D24/114; D24/222

(58) **Field of Classification Search** D24/108,
D24/112, 114, 130, 133, 119, 216, 222, 223;
435/286.1, 286.2, 286.3, 286.6, 283.1, 284.1,
435/307.1; 422/63, 100; 604/162; 506/32

See application file for complete search history.
